UNITED STATES PATENT OFFICE.

WILLIAM WILSON, OF BROOKLYN, ASSIGNOR TO GEORGE A. CLARK & BRO.,
OF NEW YORK, N. Y.

DESIGN FOR A SPOOL-THREAD CABINET.

SPECIFICATION forming part of Design No. 19,086, dated May 7, 1889.

Application filed December 28, 1888. Serial No. 294,872. Term of patent 14 years.

To all whom it may concern:

Be it known that I, WILLIAM WILSON, a citizen of the United States, residing in the city of Brooklyn, in the county of Kings and State of New York, have invented and produced a new and original Design for Spool-Thread Cabinets, of which the following is a specification, reference being had to the accompanying drawing, forming part thereof.

10 The drawing represents an isometrical perspective of a spool-thread cabinet formed according to my design, one of the drawers being shown as partly withdrawn.

My design consists in the shape and surface 15 ornamentation of a spool-thread cabinet, the leading features of which are, viz., the shape of a parallelopipedon, except that the upper surface, A, is horizontal for about one-quarter only of its width, extending its entire length, 20 while the remaining portion thereof, a' , is

truncated, beveled, or inclined downward slightly from said horizontal portion.

The surface ornamentation is as follows: the railing or molding a^2 , which surmounts the horizontal portion a around its outer 25 edge, the two panels in each side, the front of the face of the drawers D D, arranged in two series, each containing an equal number (three or four,) and the rounded edge knobs, one at each extremity of the face of each 30 drawer.

What I claim is—

A design for a spool-thread cabinet, as herein described, and shown in the accompanying drawing.

WILLIAM WILSON.
